UNITED STATES PATENT OFFICE.

LEONARD MORDANO, OF NEW YORK, N. Y.

SAFETY APPLIANCE FOR AUTOMOBILES, ETC.

Application filed April 29, 1921. Serial No. 465,592.

To all whom it may concern:

Be it known that I, LEONARD MORDANO, a subject of the Sultan of Morocco, (having declared my intention of becoming a citizen 5 of the United States), and a resident of the borough of Manhattan, city, county, and State of New York, have invented certain new and useful Improvements in Safety Appliances for Automobiles, Etc., of which 10 the following is a specification.

Primarily, the object of my invention is to prevent the surreptitious operation or use of an automobile, auto-truck or similar motor vehicle; and secondarily, to give audible warning of any attempt to do so; both of which results I attain by means of a manipulatory rotative dial spindle and accessories adapted to open and close the electric sparking circuit, and the electric alarm 15 circuit, in the manner and for the purposes hereinafter fully set forth,—the invention consisting essentially in the specific combination and arrangement of parts and elements described and claimed, and a distinctive feature being the adaptation of the principle of the permutation lock to safeguard the vehicle by the control of said electric circuits substantially as exemplified in connection with the accompanying drawings.

30 In the accompanying drawings,

Fig. 1, is a front elevation of my safety appliance as positioned on the dash-board, or other fixed part, of a vehicle of the character designated;

35 Fig. 2, is a central vertical section taken upon plane of line 2—2, Fig. 1;

Fig. 2^a, is a sectional detail showing a modification of certain parts shown in Fig. 2;

40 Fig. 3, is a rear elevation of the device;

Fig. 4, is a sectional elevation taken upon plane of line 4—4, Fig. 2;

Fig. 5, is a sectional elevation taken upon plane of line 5—5, Fig. 2;

45 Fig. 6, is a sectional elevation taken upon plane of line 6—6, Fig. 2;

Fig. 7, is a sectional elevation taken upon plane of line 7—7, Fig. 5;

50 Fig. 8, is a diagram illustrating the electric circuits involved;

Fig. 9, is an edge elevation of one of the permutation arms or tumblers;

55 Fig. 9^a, is an elevation thereof, taken at right angles to Fig. 9, and broken away in part;

Fig. 10, is a sectional detail, upon an en-

larged scale, taken upon plane of line 10—10, Fig. 4;

Fig. 11, is a sectional detail, on a similar enlarged scale, taken upon plane of line 60 11—11, Fig. 4;

Fig. 12, is a sectional detail taken upon plane of line 12—12, Fig. 11;

Fig. 13, is an elevation, partly in section, of the basic structure of my device, with 65 the operative parts omitted, but showing the electrical contact plates, etc.;

Fig. 14, is a sectional elevation taken upon plane of line 14—14, Fig. 13;

Fig. 15, is a sectional elevation taken 70 upon plane of line 15—15, Fig. 13;

Fig. 16, is a sectional elevation taken upon plane of line 16—16, Fig. 13;

Fig. 17, is a perspective view of one of the 75 contact plates;

Fig. 18, is an elevation, in part, similar to Fig. 13, showing a modification.

D, represents a portion of a dash-board, or other conveniently available fixed support, on which my safety appliance may be mounted, said support D, being formed with an opening or recess d, for the accommodation of the basic structure B, of the device, said basic portion consisting essentially of a relatively hollow cylindrical container block 80 85 of non-conductive material, as shown more particularly in Figs. 13 to 16 inclusive, and designated hereinafter, for convenience, as the base block B.

To this base block B, is secured the annular face plate F, by means of screws b, b; and the face plate F, is in turn screwed (as at f, f) or otherwise rigidly attached to the support D, as shown in Figs. 1 and 2. A casing C, indicated by dotted lines in Fig. 95 2, encloses the rear of the base block B, and the parts mounted thereon.

The central opening f', in the annular face plate F, accommodates the shank s, of the permutation-dial-spindle S, which is formed 100 with the conoidal dial head s', having the knob s², for manipulative purposes,—said spindle S, being rotatably mounted on the face plate F, by means of a split annular bearing plate e, having a bevelled inner edge e', which contacts with the bevelled edge s³, of the spindle head s', as shown more particularly in Fig. 2,—the split or space between the ends of said annular bearing plate e, being occupied by a sectional clamping plate e², provided with a set screw e³, the threaded shank of which engages with 105 110

a female thread formed for the purpose in the underlying portion of the face plate F, thus affording means whereby the spindle S, may be held rigidly in a prescribed position, and against rotation, when desired.

The peripheral edge s^3 , of the dial head s' , of the permutation spindle S, is formed with a scale s^x , (Fig. 1) consisting of a series of figures or other marks for use in connection with a pointer or indicator z , on the bearing plate e, as a means for setting or prescribing the axial position of said spindle S, and its shank s, as related to the operative parts positioned within the base 15 block B.

On said shank s, of the rotatable spindle S, is positioned a sleeve i, of insulating material, the inner end of said shank s, and its said insulating sleeve i, being supported 20 and centralized by a bearing b', formed for the purpose in the rear wall of the base block B. This insulating sleeve i, may be rigidly attached to the shank s, of the permutation spindle S, as in Fig. 2, by a screw i', passing through said sleeve I, and screwing directly into the shank s, or, as in the modification shown in Fig. 2^a, a binding screw i², may be employed to engage a thread formed for the purpose in the end of the 25 shank s, the head of the screw i², pressing against the rear end of the insulating sleeve i, and thereby holding it against rotation on the spindle shank s. In either case the shifter-arm j, is rigidly affixed to said sleeve 30 i, so as to rotate therewith.

The function of said shifter arm j, is to turn the electric circuit switch plates k', k², either to the right or left, according to the direction in which the permutation 40 spindle S, is manipulated through the medium of the knob s². To this end, the said switch plates k', k², are mounted loosely upon the sleeve i, so as to be independently rotatable thereon. That is to say, the hub 45 sleeve k'', of the first switch plate k', is mounted loosely but directly upon the insulating sleeve i, while the hub sleeve k²², of the second switch plate k², is mounted directly and loosely upon said hub sleeve k''', of the first named switch plate k', as shown more particularly in Figs. 2 and 2^a. l', l², are spring latches pivotally mounted on the switch plates k', k², which yield to the shifter-arm j, in one direction only, as 50 will be understood by reference more particularly to Fig. 11, of the drawings. Thus the switch plate k', can be rotated by the shifter-arm j, only in the direction of the solid arrow x, Fig. 4, while the other switch 55 plate k², can be rotated only in the opposite direction by said shifter arm j, as indicated by the dotted arrow x', Fig. 4.—it being understood that the latches l', l², are reversed as related to each other, and that the con- 60 tactual engagement of the hub sleeves k'', 65

and k²², with each other and with the insulating sleeve i, affords sufficient frictional resistance to hold the said switch plates k', k², against rotation unless positively manipulated by means of said shifter arm 70 j; and that the springs which bear against the latches l', l², while having sufficient resilient force to hold said latches in normal position, are of insufficient strength to overcome said frictional contactual resistance between the hub sleeves of the switch plates k', k², and the insulating sleeve above set forth. Hence each of said switch plates k', k², is rotatable only in one direction, and that in opposition to the direction of rotation of the other switch plate. 75

g, g^x, are terminal contact plates which are positioned on diametrically opposite sides of the base block B, as shown in Figs. 2, 4, 13, 14 and 16, being held in position 80 thereon by screws g', g², the inner ends of which also act as binding posts for circuit wires,—lock nuts g³, g³, being provided for the purpose, as shown particularly in Fig. 2, of the drawings. The upper screw post g', is connected directly by wire q', with the battery q, (Fig. 8) or other source of electricity, while the other post g², is connected (see g⁴, Fig. 6) with the coil of the electro-magnet m, which in turn is connected 85 electrically, as at g⁵, with the twin magnet m', the coil of which is grounded through the connection g⁶, Fig. 6, thus completing and closing the magnetic circuit when the two switch plates k', k², are positioned with 90 their contact arms k^{x1}, k^{x2}, in electrical engagement with the aforesaid diametrically opposed contact plates g, g^x, as shown in Figs. 2 and 4.

By preference, I employ a magnetic circuit of the character designated herein to control the sparking circuit, although the latter might be controlled direct by the switch plates k', k², if preferred. 105

As shown in the drawings, the cores m^x, m^x, of the magnets m, m', when energized, actuate an armature a, pivotally suspended between bracket members b², b², rigidly attached to the rear wall of the base block B. Normally the armature a, is held in retracted position by means of a spring a', which causes stops a², a², on the hub of the armature a, to rest against the upper edges of the bracket members b², b², as indicated in Figs. 2, 3, and 5. On the armature a, is secured an insulating plate a³, to which is attached a bridge plate a⁴, having yieldably mounted thereon contact studs a⁵. That is to say, said contact studs a⁵, as shown more particularly in Fig. 7, have coiled springs 110 a⁶, interposed between their heads a⁵¹, and the insulating plate a³, the thrust of the springs a⁶, being limited by nuts a⁷, on the threaded rear ends of the studs. This elastic resilient support of the contact studs 115

a^5 , enables them to press positively against the terminal plates h , h' , of the electric horn circuit without impeding the motion or function of the armature a , as actuated and controlled by the electro-magnets m , m' .

The terminal plates h , h' , are secured to the rear wall of the base block B, by means of screws h^2 , h^3 , which also connect said terminal plates h , h' , electrically (as by h^{22} , h^{33} , 10 Fig. 13) with the segmental contact plates h^4 , h^5 , mounted in and on the said base block B, as indicated more particularly in Fig. 13 of the drawings. The contact plate h^4 , is electrically connected by the conductor h^{41} , with the binding screw g' , which is in direct electrical connection with the battery q' or other source of electricity, as heretofore stated in connection with the magnetic circuit. The contact plate h^5 , is electrically connected by a conductor h^{51} , with another segmental contact plate h^6 , from which a grounding conductor h^7 , extends.

It is to be noted that the several contact plates g , g^x , h^4 , h^5 , and h^6 , are arranged concentrically as related to the permutation spindle S, and its shank s^2 , and within the path of the contact arms k^{x1} , k^{x2} , of the two switch plates k' , k^2 , as rotated by the shifter arm j . The spaces b^x , b^x , between the adjacent ends of said contact plates g , g' , h^4 , h^5 , and h^6 . (see particularly Fig. 13) constitute neutral areas in which the said contact arms k^{x1} , k^{x2} , of the switch plates k' , k^2 , are inoperative in the sense that when either 30 of said contact arms k^{x1} , k^{x2} , is so positioned in any of said neutral spaces b^x , b^x , no current can pass through the switch plates k' , k^2 , which latter are unitary in function. That is to say, the two switch plates act in 40 conjunction to form a bridge for the passage of an electrical current when their contact arms k^{x1} , k^{x2} , are in electrical engagement with opposite circuit terminals, and in this respect they differ from the ordinary circuit opening and closing switch or key. Thus in Figs. 2 and 4, their contact arms k^{x1} , k^{x2} , are shown as in electrical engagement with the contact plates g , g^x , thereby closing the electro-magnetic circuit 50 which controls the sparking circuit.

The shifter arm j , is of course set upon the shank s , of the permutator spindle S, with relation to the scale s^x , on the dial head s' , of the latter, in such manner that a prescribed combination of figures has to be effected by the manipulation of said dial as related to the pointer z , Fig. 1, in order to close the magnetic circuit through the medium of the switch plates k' , k^2 . For instance, for convenience of illustration, we will suppose that the combination is o , and 50, as in Figs. 1, 2 and 4, in which the terminal plates g , g^x , are positioned diametrically on opposite sides of the spindle S. If, 60 however, a different combination is desired

the same may be obviously attained either by shifting the contact plates g , or g^x , or by adjusting the shifter arm j , on the shank s , of the spindle. For instance, referring to Fig. 18, it is obvious that if the contact plate g , 70 be shifted to either of the positions indicated by g'' , g''' , therein, the timing of contact with relation to the dial s' , will be altered accordingly, which illustrates one method of varying the operative combination, the knowledge of which is essential in order to render the sparking circuit of the motor effective. Or, referring now to Fig. 2^a, the binding screw i^2 , may be loosened, and the insulating sleeve i , and shifter arm j , turned 75 more or less with relation to the dial index s^x , with like result. In either case the parts are set with relation to the spark-controlling-circuit, which is inoperative until the proper permutation combination is effected, and only so while it is maintained; for which reason the clamping plate e^2 , and set screw e^3 , are provided as a means of holding the set parts against accidental displacement 80 during the legitimate use and operation of the motor vehicle.

When it is desired to safeguard the vehicle and motor against illicit use of any kind, the set screw e^3 , is loosened, and the spindle S, turned to the right or left, shifting one or both of the contact arms k^{x1} , k^{x2} , of the switch plates k' , k^2 , out of engagement with the terminal contact plates g , g^x .

Obviously, while either one or both of said contact arms k^{x1} , k^{x2} , occupy any one of the neutral areas b^x , b^x , in their annular path, no electric current can pass through the switch plates k' , k^2 , but if contact is made simultaneously with the terminal plate h^4 , and either of the contact plates h^5 , h^6 , the electric horn circuit will be closed, and an alarm sounded continuously until the circuit is again broken by the shifting of the switch plates k' , k^2 . By this means any clandestine tampering with the permutation spindle S, will be promptly signalled, because in efforts to learn and locate the operative combination the usurper is bound to rotate the spindle more or less in opposite directions, thereby insuring the closing of the horn circuit as above set forth.

It will thus be seen that I not only render a knowledge of the working permutation combination absolutely essential to the operation of the motor through the medium of the electro-sparker circuit, but that I also incidentally insure audible notice of any unlawful tampering therewith by my provision of means whereby the horn is thrown into action by any one "feeling" for said sparking combination. At the same time, provision is made by the neutral areas b^x , b^x , for the legitimate opening of both sparking circuit and horn circuit as herein set forth.

It is to be understood of course, that the

- horn circuit may be closed manually as desired by the usual means (indicated at h^x , in Fig. 8) independent of the switch plates k' , k^2 , in my safety appliance.
5. By the term "permutation" spindle and mechanism as herein set forth by way of exemplification, I mean to designate any adaptation of the permutative principle involved, without confining myself to the 10 identical form and construction of parts shown, since it is obvious that modifications thereof may be resorted to without departing from the spirit and intent of my invention in this respect.
15. I have herein shown and described an auxiliary electric circuit independent of the sparker circuit, and arranged, upon closure by the rotatable switch plates k' , k^2 , to sound an electric horn, which latter is however used symbolically to represent any 20 other electrical sounding device that may be substituted therefor with like result.
- It is of course to be understood that the scale s^x , might be transferred to the inner 25 edge of the bearing plate p , and the pointer z , be positioned on the dial s' , with like result in so far as the operative function of the permutation spindle S , is concerned.
- By the use of the electro-magnetic circuit 30 with twin magnets m , m' which, when energized, attract the armature a , and thereby close the direct motor sparking circuit, I attain a quicker and more positive control of the sparking circuit, and avoid the necessity 35 for adjustments for wear, etc.
- What I claim as my invention and desire to secure by Letters Patent is,
1. In a safety appliance of the character designated, the combination of a permutation dial spindle, a shifter arm rigidly connected therewith, an insulating sleeve interposed between said spindle and said shifting arm, switch plates independently rotatable in opposite directions on said spindle and 40 fixed contact plates forming the terminals of an electric circuit controlling motor sparking means, for the purpose described.
  2. In a safety appliance of the character designated, the combination of a permutation dial spindle, a shifter arm rigidly connected therewith, an insulating sleeve interposed between said spindle and said shifting arm, switch plates independently rotatable in opposite directions on said spindle 45 and fixed contact plates forming terminals of an electro-magnetic circuit controlling direct circuit sparking means, for the purpose described.
  3. In a safety appliance of the character 50 designated, the combination of a permutation dial spindle, a shifter arm mounted thereon, an insulating sleeve interposed between said spindle and said shifting arm, means for effecting the adjustment of said shifter arm with relation to the dial of said 55 spindle, switch plates independently rotatable in opposite directions on said spindle, and fixed contact plates forming the terminals of an electric circuit controlling motor sparking means, for the purpose described. 70
  4. In a safety appliance of the character designated, the combination of a permutation dial spindle, a shifter arm mounted thereon, an insulating sleeve interposed between said spindle and said shifting arm, switch plates independently rotatable in opposite directions on said spindle, means for securing the latter against rotation, and fixed contact plates forming the terminals of an electric circuit controlling motor sparking means, for the purpose described. 75
  5. In a safety appliance of the character designated, the combination of a permutation dial cylinder, a shifter arm mounted thereon, an insulating sleeve interposed between said spindle and said shifting arm, means for effecting the adjustment of said shifter arm with relation to the dial of said spindle, switch plates independently rotatable in opposite directions on said spindle, 80 means for securing the latter against rotation, and fixed contact plates forming the terminals of an electric circuit controlling motor sparking means, for the purpose described. 85
  6. In a safety appliance of the character designated, the combination of a permutation dial spindle, a shifter arm mounted thereon and rotatable therewith, an insulating sleeve interposed between said spindle and said shifting arm, switch plates independently rotatable in opposite directions on said spindle, 90 means for securing the latter temporarily against rotation, and fixed contact plates forming the terminals of an electric circuit controlling motor sparking means, for the purpose described. 95
  7. In a safety appliance of the character designated, the combination of a permutation dial spindle, a shifter arm mounted thereon and rotatable therewith, an insulating sleeve interposed between said spindle and said shifting arm, means for effecting their rotation in opposite directions by the shifter arm, and fixed contact plates forming the 100 terminals of an electric circuit controlling motor sparking means, for the purpose described. 105
  8. In a safety appliance of the character designated, the combination of a permutation dial spindle, a shifter arm mounted thereon and rotatable therewith, an insulating sleeve interposed between said spindle and said shifting arm, means for effecting their rotation in opposite directions, by the shifter arm, and fixed contact plates forming the 110 terminals of an electric circuit controlling motor sparking means, for the purpose described. 115
  9. In a safety appliance of the character designated, the combination of a permutation dial spindle, a shifter arm mounted thereon and rotatable therewith, an insulating sleeve interposed between said spindle and said shifting arm, means for effecting the adjustment of said shifter arm with relation to the dial on said spindle, switch plates independently rotatable on said spindle, 120 means for effecting their rotation in opposite directions, by the shifter arm, and fixed contact plates forming the terminals of an electric circuit controlling motor sparking means, for the purpose described. 125
  10. In a safety appliance of the character designated, the combination of a permutation dial spindle, a shifter arm mounted thereon and rotatable therewith, an insulating sleeve interposed between said spindle and said shifting arm, means for effecting the adjustment of said shifter arm with relation to the dial of said 130

- tion to the dial on said spindle, means for securing the latter temporarily against rotation, switch plates independently rotatable on said spindle, means for effecting their rotation in opposite directions by means of the shifter arm, and fixed contact plates forming the terminals of an electric circuit controlling motor sparking means, for the purpose described.
9. In a safety appliance of the character designated, the combination of a permutation dial spindle, a shifter arm mounted thereon and rotatable therewith, an insulating sleeve interposed between said spindle and said shifting arm, means for effecting the adjustment of said shifter arm with relation to the dial on said spindle, means for securing the latter temporarily against rotation, switch plates independently rotatable on said spindle, means for effecting their rotation in opposite directions by means of the shifter arm, and fixed contact plates forming the terminals of an electric circuit controlling motor sparking means, together with fixed contact plates in concentric alignment with the permutation dial spindle and forming the terminals of an electric alarm sounding device, for the purpose described.
10. In a safety appliance of the character designated, the combination of a permutation dial spindle, a shifter arm rigidly connected therewith, an insulating sleeve interposed between said spindle and said shifting arm, switch plates independently rotatable in opposite directions on said spindle and fixed contact plates forming the terminals of an electric circuit controlling motor sparking means, together with fixed contact plates in concentric alignment with the permutation dial spindle and forming the terminals of an electric alarm sounding device, for the purpose described.
11. In a safety appliance of the character designated, the combination of a permutation dial spindle, a shifter arm rigidly connected therewith, an insulating sleeve interposed between said spindle and said shifting arm, switch plates independently rotatable in opposite directions on said spindle and fixed contact plates forming terminals of an electro-magnetic circuit controlling direct circuit sparking means, together with fixed contact plates in concentric alignment with the permutation dial spindle and forming the terminals of an electric alarm sounding device, for the purpose described.
12. In a safety appliance of the character designated, the combination of a permutation dial spindle, a shifter arm mounted thereon, an insulating sleeve interposed between said spindle and said shifting arm, means for effecting the adjustment of said shifter arm with relation to the dial of said spindle, switch plates independently rotatable in opposite directions on said spindle, and fixed contact plates forming the terminals of an electric circuit controlling motor sparking means, together with fixed contact plates in concentric alignment with the permutation dial spindle and forming the terminals of an electric alarm sounding device, for the purpose described.
13. In a safety appliance of the character designated, the combination of a permutation dial spindle, a shifter arm mounted thereon, an insulating sleeve interposed between said spindle and said shifting arm, switch plates independently rotatable in opposite directions on said spindle, means for securing the latter against rotation, and fixed contact plates forming the terminals of an electric circuit controlling motor sparking means, together with fixed contact plates in concentric alignment with the permutation dial spindle and forming the terminals of an electric alarm sounding device, for the purpose described.
14. In a safety appliance of the character designated, the combination of a permutation dial cylinder, a shifter arm mounted thereon, an insulating sleeve interposed between said spindle and said shifting arm, means for effecting the adjustment of said shifter arm with relation to the dial of said spindle, switch plates independently rotatable in opposite directions on said spindle, means for securing the latter temporarily against rotation, and fixed contact plates forming terminals of an electric circuit controlling motor sparking means, together with fixed contact plates in concentric alignment with the permutation dial spindle and forming the terminals of an electric alarm sounding device, for the purpose described.
15. In a safety appliance of the character designated, the combination of a permutation dial spindle, a shifter arm mounted thereon and rotatable therewith, an insulating sleeve interposed between said spindle and said shifting arm, switch plates independently rotatable on said spindle, means for effecting their rotation in opposite directions by the shifter arm, and fixed contact plates forming the terminals of an electric circuit controlling motor sparking means, together with fixed contact plates in concentric alignment with the permutation dial spindle and forming the terminals of an electric alarm sounding device, for the purpose described.
16. In a safety appliance of the character designated, the combination of a permutation dial spindle, a shifter arm mounted thereon and rotatable therewith, an insulating sleeve interposed between said spindle and said shifting arm, means for effecting the adjustment of said shifter arm with relation to the dial on the said spindle, switch plates independently rotatable on said

spindle, means for effecting their rotation in opposite directions by the shifter arm, and fixed contact plates forming the terminals of an electric circuit controlling motor 5 sparking means, together with fixed contact plates in concentric alignment with the permutation dial spindle and forming the terminals of an electric alarm sounding device, for the purpose described.

10 17. In a safety appliance of the character designated, the combination of a permutation disc spindle, shifter arm mounted thereon and rotatable therewith, an insulating sleeve interposed between said spindle and

said shifting arm, switch plates independently rotatable on said spindle, means for effecting their rotation in opposite directions by the shifting arm, fixed contact plates forming the terminals of an electro-magnetic circuit, and an electric circuit controlled by said electro-magnetic circuit and in turn controlling motor sparking means, for the purpose described.
